Primary Examiner — Cathron C Brooks*Assistant Examiner* — W. A. Teddy Falloway(74) Attorney, Agent, or Firm — Dunlap Bennett & Ludwig PLLC(57) CLAIM

The ornamental design for a military pouch, as shown and described.

DESCRIPTION

FIG. 1 is a top front perspective view of a military pouch; FIG. 2 is a front elevation view thereof; FIG. 3 is a rear elevation view thereof; FIG. 4 is a top plan view thereof; FIG. 5 is a bottom plan view thereof; and, FIG. 6 is a right elevation view of FIG. 1, the left elevation view being a mirror image thereof.

The broken lines shown in the drawings depict portions of the military pouch that form no part of the claimed design.
